United States Patent

Des. 240,589
Patented July 20, 1976

240,589

ROTATABLE LOCKING JOINT

Lonnie D. Cooper, Hawthorne, Calif., assignor to
Revell, Incorporated, Venice, Calif.

Filed Sept. 23, 1974, Ser. No. 508,106

Term of patent 14 years

FIG. 1 is a plan view of a rotatable locking joint in its open position;

FIG. 2 is a front elevation taken along lines 2—2 of FIG. 1;

FIG. 3 is a right side elevation taken along lines 3—3 of FIG. 1; and

FIG. 4 is a view of the bottom of the rotatable locking joint.

I claim:

The ornamental design for a rotatable locking joint, as shown.
